UNITED STATES PATENT OFFICE

172,412

SPECTACLE FRAME FRONT

Harry Weissman, New Hyde Park, N. Y.

Application November 23, 1953, Serial No. 27,728

Term of patent 14 years

(Cl. D57—1)

To all whom it may concern:

Be it known that I, Harry Weissman, a citizen of the United States and resident of New Hyde Park, in the county of Nassau and State of New York, have invented a new, original, and ornamental Design for a Spectacle Frame Front, of which the following is a specification, reference being had to the accompanying drawing, forming part hereof.

Fig. 1 is a front elevational view of a spectacle frame front, showing my new design.

Fig. 2 is a front elevational view of the ornamentation portion of the spectacle frame front on the left side of Fig. 1, shown removed therefrom and taken on an enlarged scale.

Fig. 3 is a side elevational view of the ornamentation portion thereof, taken from the right side of Fig. 2.

Fig. 4 is a top plan view of the ornamentation portion thereof, shown in Fig. 2.

The dominant feature of my design resides in the portions shown in full lines.

I claim:

The ornamental design for a spectacle frame front, substantially as shown and described.
